CLAIM

The ornamental design for a gun barrel rest with pistol rack, as shown and described.

DESCRIPTION

FIG. 1 is a front perspective view of the gun barrel rest with pistol rack of the present invention;

FIG. 2 is a right side elevation view of the gun barrel rest with pistol rack of the present invention;

FIG. 3 is a left side elevation view of the gun barrel rest with pistol rack of the present invention;

FIG. 4 is a front elevation plan view of the gun barrel rest with pistol rack of the present invention;

FIG. 5 is a rear elevation plan view of the gun barrel rest with pistol rack of the present invention;

FIG. 6 is a top plan view of the gun barrel rest with pistol rack of the present invention;

FIG. 7 is a bottom plan view of the gun barrel rest with pistol rack of the present invention;

FIG. 8 is a front perspective view of a second embodiment of the gun barrel rest with pistol rack of the present invention;

FIG. 9 is a right side elevation view of a second embodiment of the gun barrel rest with pistol rack of the present invention;

FIG. 10 is a left side elevation view of a second embodiment of the gun barrel rest with pistol rack of the present invention;

FIG. 11 is a front elevation plan view of a second embodiment of the gun barrel rest with pistol rack of the present invention;

FIG. 12 is a rear elevation plan view of a second embodiment of the gun barrel rest with pistol rack of the present invention;

FIG. 13 is a top plan view of a second embodiment of the gun barrel rest with pistol rack of the present invention; and, FIG. 14 is a bottom plan view of a second embodiment of the gun barrel rest with pistol rack of the present invention. The portions of the gun barrel rest with pistol rack shown in broken lines form no part of the claimed design.
